**PIPE CABLE AND CONDUIT LAYING AND
EXTRACTING DEVICE OR THE LIKE**

William Maynard Slaughter, Rte. 3,
Fuquay-Varina, N.C. 27526

Filed May 24, 1971, Ser. No. 146,581

Term of patent 14 years

Int. Cl. D12—05

U.S. Cl. D12—56

FIG. 1

FIG. 2

FIG. 3

FIG. 4

FIG. 5

FIG. 1 is a side perspective view of a pipe, cable and conduit laying and extracting device or the like showing my new design;

FIG. 2 is a reverse side perspective view of such design;

FIG. 3 is a front perspective view of the same;

FIG. 4 is a rear perspective view of such design; and

FIG. 5 is a front perspective view of the same.

I claim:

The ornamental design for a pipe, cable and conduit laying and extracting device or the like, as shown.
